UNITED STATES PATENT OFFICE.

GEORGE J. SEISS, OF TOLEDO, OHIO.

AUTOMOBILE HORN.

Application filed August 6, 1923. Serial No. 655,810.

My invention has for its object to provide an electromagnetically operated horn wherein the parts are so constructed that they may be easily assembled and adjusted 5 and efficiently made, and whereby efficient horns may be manufactured at a low cost of production.

A horn containing the invention is illustrated in the accompanying drawings and is 10 described in the following description.

Figure 1 of the drawings is a view of the electromagnet, the covering shell being shown removed therefrom. Fig. 2 is a side view of the horn. Fig. 3 is a sectional view 15 taken on the line 3—3 indicated in Fig. 1. Fig. 4 illustrates a means whereby two of the parts may be readily locked together in the manufacture of the horn. Fig. 5 illustrates a side view of the horn a part of the 20 clamping flange being shown to clearly show the three main parts of the horn. Fig. 6 illustrates a vertical sectional view of the horn taken between the connector plate and the supporting plate and looking towards 25 the connector plate. Fig. 7 illustrates a side view of the armature and shows its pivotal connection to the supporting plate.

The horn is provided with the usual trumpet, resonator or megaphone 1 and the 30 diaphragm 2, located in position to produce the desired air vibration at one end of the mouth or resonator of the horn. The diaphragm 2 is secured in position by spinning the sheet metal along the edge portion 3 over 35 the edge of the diaphragm. In the construction shown, a supporting plate 4 is also secured in position in contact with or in close proximity to the diaphragm 2 by spinning or crimping the edge portion of the resonator 40 of the horn over the edges of the plate and the diaphragm.

The supporting plate 4 is provided with a plurality of projecting parts that are struck up from the plate 4 on which the parts of 45 the structure are supported so that they may function one with the other. The electromagnets 5 and a connector plate 6 are supported on the parts 7 that are struck up from the plate 4. These parts are secured together 50 by riveting the ends of the cores 8 of the magnet after they have been inserted through the parts 7 and a flange 9 that is struck up from the connector plate 6. The other end of the connector plate is also provided 55 with an upwardly extending flange 10, and binding posts 11 are secured to the

flange 10. They are insulated from the connector plate 6 by suitable insulating material 12. Wires from the electromagnets are connected to the binding posts and also to 60 connecting members 13 and 14. The connector member 13 is located at the end of a leaf spring 15 and operates to secure one end of the spring to the connector plate 6. The spring 15 protrudes through an opening 16 65 formed in the body of the connector plate and in the flange 9, and beneath a lug 17 that is formed from the space that forms the opening through which the spring 15 extends to a point between the electromagnets 5. This 70 leaves a small amount of metal at the upper corners of the opening 16 that may be readily bent by the use of a pair of pincers to adjust the position of the lug 17 relative to the spring 15. A contact 18 is supported 75 on the spring 15 and a contact 19 is supported on the lug 17 and suitably insulated therefrom. The contact 19 electrically connects with the connector member 14 that is connected to one of the electromagnets 5, so 80 that the position of the contacts 18 and 19 may be readily adjusted by simply gripping that portion of the flange 9 located above the lug 17 and bending the flange at this point so as to move the lug 17 either up or down or 85 swinging it laterally or even rearwardly or forwardly to properly adjust the contacts 18 and 19 relative to each other to produce a full and complete contact over substantially the entire areas of the contacting surfaces of 90 the contacts.

The armature 20 is pivotally supported in the parts 21 that are struck up from the plate 4. The armature 20 is provided with an arm 22 that extends substantially to the center of the diaphragm 2. The end 23 of the arm, being turned substantially along the axis of the horn and entering an opening through the plate 4, is positioned for striking the horn when the magnets are energized. The arm 22 of the armature 20 is provided with a rivet 24 having a flanged head 25 that engages the end of the leaf spring 15. A flat spring 26 is secured to the arm 22 by means of the riveted member 24. The spring 26 enters an opening formed in the portion 27 that is struck up from the plate 4. The spring 26 is so bent that when the armature is inserted in place and the spring is inserted in the opening 28 formed in the portion 27 the spring operates to elastically hold or retain the armature 20 in the desired position 110.

tion relative to the poles of the electromagnet.

The portion 27 is also provided with a slot or cut 29 that fits a slot 30 formed in the connector plate 6 so that when the magnets 5 and the connector plate 6 are secured in position the connector plate is first slid over the end of the portion 27, while at the same time it is moved laterally so that the slots 10 29 and 30 will permit interengagement of the end of the portion 7 with the body portion of the connector plate 6, and then the ends of the cores of the magnets are riveted to the connector plates after having been 15 inserted through the portions 7 that are struck up from the plate 4.

The invention thus provides a construction that may be readily and rapidly assembled in the manufacture of automobile horns. 20 The connector plate 6 carries the connecting parts, such as the binding post 11 and the wire connecting members 13 and 14. These are the parts that are connected to the terminals of the coils of the magnets 5. The 25 connector plate 6 and the parts connected therewith may be readily assembled in position and then placed on the supporting plate 4 and secured in position by means of the rivets that may be formed at the ends of the 30 cores of the magnets. The wires may then be connected to the connecting members and to the binding posts. This completes the assemblage of this part of the structure. The armature may then be inserted between 35 the portions 21 of the plate 4 and the portions 21 bent towards each other so as to engage the pivot pins of the armature and thus pivotally support the armature in position. At the same time that the armature is 40 inserted in position, the spring 26 may be inserted in the opening 28 of the portion 27, and the flanged head 25 may be inserted over the end of the spring 15 and in position to engage the spring when the armature is 45 operated by the electromagnet. Therefore to assemble the parts the electromagnets are riveted to the connector plate through the flange 9 of the connector plate and the armature 20 is inserted in position, and the portions 21 are bent up so as to engage the pivot pins of the armature.

The only adjustment required in the mechanism is the position of the contacts 18 and 19 relative to each other. In order to 55 make a full and complete contact, that is, in order to cause the contact 18 to strike the contact 19 squarely, some adjustment may be required. This may be accomplished by bending the portion 31 of the flange 9 located directly above the opening 16, whereby

the lug 17 may be moved lateral or bent upward so as to enable the contacts 18 and 19 to make good contact with each other. The invention thus provides an exceedingly efficient horn that may be manufactured in 65 large quantities at a low cost of production.

The cover 32 may be secured in position by lugs 33 that are struck up from the supporting plate 3. Preferably three such lugs 70 are used to engage a flaring edge portion that is formed on the shell cover 32. The operative parts of the mechanism may thus be covered by inserting the edge of the cover under two of the lugs and snapping the edge under the third lug. 75

I claim:

1. In an automobile horn, a main supporting plate, ears struck up from the main supporting plate, a connector plate and a magnet supported by the ears, a pair of insulated binding posts and an elastic movable contact member and a fixed insulated contact member secured to the connector plate, an armature pivotally supported on the main supporting plate and in position to be operated upon by the electromagnet and having a part extending over the end of the elastic contact member. 80

2. In an automobile horn, a main supporting plate, ears struck up from the main supporting plate, a connector plate and a magnet supported by the ears, a pair of insulated binding posts and an elastic movable contact member and a fixed insulated contact member secured to the connector plate, an armature pivotally supported on the main supporting plate and in position to be operated upon by the electromagnet and having a part engaging the end of the elastic contact member, a shell for covering the 95 said main supporting plate and enclosing the said parts and having openings through which the binding posts extend. 100

3. In an automobile horn, a main supporting plate, ears struck up from the main supporting plate, a connector plate and a magnet supported by the ears, a pair of insulated binding posts and an elastic movable contact member and a fixed insulated contact member secured to the connector plate, an armature pivotally supported on the main supporting plate and in position to be operated upon by the electro magnet, a member secured to the armature and having a circular flange adapted to be slipped over and to engage the yielding contact member. 115

In testimony whereof, I have hereunto signed my name to this specification.

GEORGE J. SEISS.
